(57) **CLAIM**

The ornamental design for a headphone module, as shown and described.

DESCRIPTION

FIG. 1 is a front, left perspective view of a headphone module showing the new design;

FIG. 2 is a front elevation view thereof;

FIG. 3 is a rear elevation view thereof;

FIG. 4 is a left side view thereof;

FIG. 5 is a right side view thereof;

FIG. 6 is a top plan view thereof;

FIG. 7 is a bottom plan view thereof; and,

FIG. 8 is an alternative front elevation view thereof, with the ear cups in a retracted position.

The broken dashed lines form no part of the claimed design.
